OIL BURNER

Application filed December 10, 1929, Serial No. 413,004, and in Japan December 31, 1928.

This invention relates to an oil burner, wherein a number of perpendicular pipes having their lower ends open in the space between the outer and inner perforated tubes 5 and their upper ends communicating with a vaporizing chamber at the upper part of the inner tube, are inserted in several vertical channels around the inner tube and wherein fuel oil is supplied to the vaporizing chamber in a dripping condition. The object thereof is to obtain a device which prevents the oil from reaching the burner in a liquid form by gasifying it perfectly and consequently is suitable especially for low class 10 oils.

Referring to the accompanying drawings, Figure 1 is a central longitudinal sectional view of the oil burner of this invention;

Figure 2, a plan of the same with parts 20 shown cut away;

Figure 3, a central longitudinal sectional view on a plane at right angles to the plane of Fig. 1; and

Figure 4, a detailed perspective of the essential parts.

In the drawings, A is the inner tube, and B the outer tube, both having their peripheries pierced with a number of holes 1. There is suitable space left between the two tubes.

Around the inner tube A are constructed several vertical channels 2 for receiving perpendicular pipes C, the upper ends of which protrude in the vaporizing chamber D around its bottom in such a manner that they can

35 be detached together with the vaporizing chamber when it is necessary to clean the burner. The vaporizing chamber D is located in the upper part of the inner tube and has a cover 3 which can be opened when it

40 is desired to clean the interior of the vaporizing chamber or to remove the pitch or the like produced by low-class oils. The pipe 4 is provided at its outer end with a hopper 5 so as to drop the oil on the bottom and the

45 oil in a tank 6 drips down from a valve 7. A pipe 8 is attached to the hopper at a position a little lower than the upper end of the perpendicular pipes C, so that the superabundant oil is discharged from it instead of flowing into the perpendicular pipes from the

vaporizing chamber, and thus the oil is prevented from reaching the burner directly. E is a cover having supporting rods 9 to hold the inner and outer tubes, at the lower parts of which a receiver F with an asbestos ring 10 is provided in such a manner as to be moved up and down by a cam 11 and also a pipe 12 and a hopper 13 for supplying the fuel oil are provided.

When petroleum, light oil, etc. flow into the hopper 13 and permeate the asbestos ring through the pipe 12, the ring is lighted, and then the flame will rise along the space between the inner and outer tubes, thus heating the vaporizing chamber at once. At this time, if the valve 7 is opened suitably, the fuel oil

55 will drip down on the bottom of the vaporizing chamber through the pipe 4. The vaporizing chamber being heated well and especially because of its bottom being connected with the upper plate of the inner tube and consequently red-heated by the conduction of heat, the dripping oil is gasified immediately. The gas thus produced fills the vaporizing chamber and goes in a reverse direction along the perpendicular pipes C so as to be superheated

60 in the space between the inner and outer tubes. Therefore, the superheated gas is in such a condition as to be ignited immediately it jets from the lower ends of a number of 65 the pipes C and ascends sucking the proper amount of air from a number of holes covering the two tubes, thereby burning perfectly.

70 Thus, as according to this invention the fuel oil is supplied in a dripping condition, it can not only be gasified at once without the necessity of heating a large quantity of oil, but as it drips down on the red-hot bottom of the vaporizing chamber, it is gasified

75 very quickly. Moreover, as the gas is conducted by the pipes protruding in the vaporizing chamber, there is no fear of the oil flowing down in a liquid form. Further, it is directed downwardly in a reverse direction by several pipes and also advances slowly in the flames in the space between the inner and outer tubes, so that it is heated to a very high temperature and burns continually, while at the lower end of the opening the gas merely jets. It then ascends in the space between 80

85 90 95 100

the inner and outer tubes having a number of holes, where it receives a sufficient supply of air to burn perfectly.

For the above reason, in the present invention it is possible to use such low class oils as heavy oil not to mention petroleum and light oil and to prevent the damage apt to be caused by dust and pitch sticking to the pipes or burners.

10 We claim:

An oil burner, comprising in combination, an inner and an outer perforated tube disposed in concentric relation, said tubes forming a combustion chamber in the space between them, the said inner tube having a number of vertical channels at its periphery, a vaporizing chamber disposed above said inner tube, a vapor conducting pipe disposed in each of said channels and communicating 15 with the vaporizing chamber at a point near its top wall, an asbestos ring disposed in the lower end of said combustion chamber, said tubes communicating with the combustion chamber immediately above said ring, means 20 for supplying fuel to said ring for initially lighting the burner, and a source of fuel supply communicating with said vaporizing chamber at a point near its bottom wall.

In testimony whereof, we have signed our 30 names to this specification at Tokyo, Japan, this 28th day of October 1929.
